EARTH ANCHOR

Thomas K. Cummins, St. Paul, Minn., assignor
to Northern Malleable Iron Company, St. Paul,
Minn., a corporation of Minnesota

Application March 5, 1936, Serial No. 67,319

9 Claims. (Cl. 189—92)

This invention relates to improvements in expandable earth anchors for guy rods, to which bracing wires for poles or like devices are secured.

An object of the invention is to substantially improve the construction of anchor devices by using a plurality of anchoring leaves and so arranging them as to obtain a maximum of anchoring ability with a minimum number of leaves. A feature is the use of two pairs of leaves, one pair arranged above an upwardly outwardly opening pair of lower leaves, and adapted to be tamped outwardly and downwardly to anchoring position after the lower leaves have been moved upwardly to anchoring position. The use of such a device results in a substantial increase in anchoring action.

Another feature is the arrangement of the axes of swing of the upper leaves in a horizontal plane and substantially at right angles to horizontally arranged axes of the lower leaves. Another feature which leads to unusual efficiency is the combination of leaves which move to anchoring position in directions opposite to one another, irrespective of what the angular relation of the axes of respective leaves may be to one another. Another feature is the pivoting of all leaves on a common support, which slides on the rod, and another feature is the arranging of the pivots of respective pairs in planes close to one another.

30 A feature is the use of a pair of leaves which can be tamped to anchoring positions after the device is in the ground and after a first anchoring means has been moved to anchoring position.

Another feature relates to means for holding 35 the guy rod to prevent sliding, when the device is introduced into the ground, with this means of such nature that it permits sliding of the rod when driving force is applied to drive the rod into the ground, as when it is desired to abandon the 40 anchor instead of bothering to dig it out. Thus, driving of the rod is possible, due to release of a temporary holding means, properly associated with the guy member and anchoring means thereon. Another feature relates to the mounting 45 of the above means on a part other than the anchor.

Objects, features and advantages of the invention will be set forth in the description of the 50 drawings forming a part of this application, and in said drawings.

Figure 1 is a side elevation showing the device in collapsed position ready to be introduced into a hole in the ground;

55 Figure 2 is an elevation taken at right angles

to Figure 1 showing one of the upper leaves partly in section to illustrate stops;

Figure 3 is a bottom plan view of the device with all leaves spread, or in anchoring position; and

Figure 4 is a vertical section taken approximately on line 4—4 of Figure 3, looking in the direction of the arrow.

Referring to the drawings, numeral 1 indicates a guy rod having the usual eye 2, and threaded 10 at its lower end as at 3 for the reception of the usual nut 4 which acts as a stop. Translatable upon the rod is a plate or head element generally indicated at 6, herein called a slide. This slide is suitably reinforced on its upper side by diametrically related ribs 7 which merge into a hollow extension 8. The guy rod passes through this extension and through the plate, as shown.

The slide has pivoted to its lower side, in any suitable manner, a pair of leaves. The particular manner of pivoting forms no part of the present invention, but it is shown as accomplished in accordance with the disclosure of Emry Patent No. 2,025,835.

Referring to Figure 4: On that face of the slide which is the lower face when the device is used, is a pair of bearings 9—10. Two anchor leaves are detachably pivotally connected with the bearings and are adapted to be spread to the position shown in Figures 3 and 4. This pivoting is accomplished by providing each leaf with a pair of trunnions and by engaging one trunnion of each leaf with each bearing, see Figure 4, the bearings and trunnions being so arranged that the trunnions can be engaged therewith by motion in an axial direction. One of the leaves is indicated at 15, the other at 16. The bearings are spaced a substantial distance apart conformably to the substantial transverse width of the leaves. For some purposes, any form of leaf 40 can be used, and there is no intention to limit the invention entirely to the kind of leaves, but the specific relations of the specific forms of leaves are also claimed.

Each lower leaf is shown as being dished on 45 that side which is faced downwardly when in anchoring position. From the concave face of each leaf project a pair of ribs 17—18, each extending beyond the inner edge of the leaf and each having projecting therefrom a trunnion. 50 The trunnions are respectively indicated at 19, 20 and 21, 22.

The leaves are thus pivoted to a slide to swing upwardly about a horizontal axis. Each leaf has also on its concave side a pair of lugs 23 and 55

means is provided for controlling spreading of the leaves to anchoring position as the slide is forcibly translated upon the rod. This controlling means includes a sleeve 25 through which the rod may slide. The sleeve is provided with a pair of perforated lugs 26, see Figure 1. Two links 28 are provided and each link has one end pivoted as at 29 between lugs 23 of the corresponding leaf. At its opposite end the link is pivoted as at 30 to one of the perforated lugs 26 of the sleeve.

It is obvious from the above description that after the device has been placed in the ground and upon applying force against the slide 6, the leaves are forced apart to anchoring position shown in Figure 3. To hold the parts in collapsed position shown in Figures 1 and 2 so that the device can be introduced into an opening in the ground without spreading the leaves, each leaf is provided with pairs of marginal openings indicated at 35. Through each pair is passed a wire 36 having its ends merely bent over as shown at 37 to temporarily but releasably secure the leaves in the position shown. When force is applied to the slide, the wire ends are released.

25 The foregoing upwardly opening leaves, in conjunction with the leaves now to be described, form the main feature of this invention. Each up-standing rib 7 has a lug 40. A second pair of leaves is provided, said leaves being indicated by the numeral 41. Each leaf is forked as at 42 to straddle the lug 40 and rib 7, and a suitable bolt 43 is passed through openings in the parts of the fork and through the lug 40 to pivotally secure the leaf. The bolt can be held against axial movement by any suitable means, but is herein shown by cross pin 44 having bent-over ends. Each leaf is provided with a stop shoulder 45 which limits its inward and upward movement at such an angular position that a tamping tool can 40 be simultaneously engaged with the inner surfaces 46 of the leaves 41. It is noted that the inner or upper faces of the leaves are concave and that in edge view, as shown in Figure 2, the outer ends of the leaves are reversely curved as at 47. 45 Each leaf is reinforced on the outer or lower side by a centrally located rib 50, and each leaf is provided with at least one opening 51. Through these openings, a wire is passed to secure the leaves in upper position shown in Figure 2, while 50 the device is being lowered into the ground. Each leaf is also provided with a second stop shoulder 53 which limits the outward and downward movement of the leaf, as shown in Figure 4. This shoulder engages with the outer end of the rib 7.

55 It is noted that in this embodiment, the horizontal pivotal axes of the upper leaves lie perpendicularly to those of the lower leaves and this is a particularly advantageous arrangement inasmuch as when both sets of leaves are in anchoring 60 position, an anchoring surface is provided which is substantially continuous over a large area. It is also noted, and this is a valuable feature, that when both sets of leaves are in anchoring position, they lie adjacent one another, that is in 65 almost the same plane, being spaced substantially only by a distance equal to the thickness of the plate 6. It is to be again noted that the upper leaves 41 are moved as a result of tamping after the lower leaves have been moved to anchoring 70 position.

The blades of the leaves 41 are released when a tamping tool engages the wire, on the first blow of the tamping tool. Repeated blows on the element 8 expand the bottom leaves of the anchor.

75 After the bottom leaves are expanded the next

operation is filling the hole with dirt. During the shoveling of the dirt the tamping tool is used and this functions to spread the leaves 41 pressing them into the solid walls of the hole. After this work has been accomplished, any pull on the anchor rod meets with resistance from the leaves 41 which enter more deeply into the solid earth, as the anchor tends to resist the pull. In this way the leaves cooperate to substantially increase the total anchoring area of the anchor. Moreover, since the leaves 41 are anchored in the side wall they resist any tendency for the bottom leaves to collapse in case these bottom leaves are not fully expanded, because of a rock or other obstruction located laterally of the walls of the 15 hole.

Another feature of the invention relates to means for preventing sliding of the rod in the sleeve 25, or its equivalent, while the device is being introduced into the hole. This sliding 20 occurs because the outer edges 55 of the lower leaves 15 catch on the sides of the holes. To prevent sliding and yet allow release of the rod when it is desired to drive it into the ground after abandonment of the anchor, means is provided on 25 the bottom of the element 25 which is releasable. The use of such a means on an anchor control element, as distinguished from its use on the anchor proper, is a valuable feature.

In this embodiment, the element 25 has a pair 30 of downward extensions 56—57, the extent of the cross-sectional area of which is shown in Figure 3. The space between these elements 56 is sufficient to easily receive the nut 4, but to prevent turning of the nut which is square. The arm 56 has on 35 its edges notches or depressions 59 and the extension 57 is provided with a rib 60 which is notched as at 61. Circumscribing these cross-sectionally elongated extensions and held in these depressions is a wire 62 secured as by twisting at 63. By 40 inspection of Figure 3, it is to be noted that the portions of the wire bridging the space between the arms are so arranged as to be engaged by the nut to prevent sliding of the rod. When using this releasable means, if the edges 55 happen to 45 strike the earth, the rod will not move downwardly because of engagement of the nut with the wires. However, when it is desired to abandon the anchor, driving force applied at the top 64 of the rod will cause the nut to break the wire to 50 allow the rod to be driven, and buried completely in the ground.

By reference to Figure 3, it is seen that the anchoring area is substantially increased. An important point is the relation of the pivoting 55 planes of the two sets of leaves, as well as the arrangement of the upper pair of leaves, whereby they can be spread to anchoring position by tamping. The scheme can and is intended to be used in combination with any type of lower 60 anchoring means and is not limited to use with the pivoted-leaf type.

I claim as my invention:

1. An earth anchor having, upper and lower separately pivoted pairs of swingable leaves the 65 lower pair adapted to swing upwardly about their pivotal points when expanded to anchoring position and the upper pair adapted to swing downwardly to anchoring position.
2. An earth anchor having, upper and lower 70 separately pivoted pairs of swingable leaves, the lower pair adapted to swing upwardly about their pivotal points when expanded to anchoring position and the upper pair adapted to swing downwardly to anchoring position, the pivotal axes 75

of respective pairs of leaves being substantially perpendicular to one another.

3. An earth anchor having a guy rod and having upper and lower pivoted pairs of swingable leaves, the lower pair adapted to swing upwardly about their pivotal points when expanded to anchoring position and the upper pair adapted to swing downwardly to anchoring position, said leaves being separately pivoted to a common support which is carried by the guy rod.

4. An earth anchor having, a guy rod and having upper and lower pivoted pairs of swingable leaves, the lower pair adapted to swing upwardly about their pivotal points when expanded to anchoring position and the upper pair adapted to swing downwardly to anchoring position, said leaves being pivoted to a common support which is carried by the guy rod, and the pivotal axes of respective pairs of leaves being substantially perpendicular to one another.

5. An earth anchor having, a guy rod and having upper and lower anchoring means, the upper means comprising a pair of separately pivoted leaves adapted to be moved outwardly and downwardly to anchoring position by means of a tool introduced between them from above, and means for releasably securing the leaves in raised non-anchoring position.

6. An earth anchor having, a guy rod and a slide thereon, said slide having upper and lower pivoted pairs of leaves, the lower pair adapted to swing upwardly about their pivotal points when expanded to anchoring position and the upper pair adapted to swing downwardly to anchoring position, and means by which motion of the slide on the guy rod swings the lower pair to anchoring position, the upper pair being adapted to be moved to anchoring position by means of a tool introduced between them from above.

7. A device of the class described comprising, a guy member, means slidably mounted thereon, and having pivoted thereto a first pair of leaves which swing upwardly on horizontal axes and a second pair of leaves which swing downwardly, means by which

the slidable means moves the lower leaves to anchoring position, and means by which said upper leaves are releasably held during anchoring engagement of the lower leaves, said upper leaves being adapted for movement to anchoring position by means of a tool introduced between them from above.

8. An earth anchor having an element slidably thereon and two pairs of anchor leaves separately pivoted on said element, said pairs being arranged to swing toward one another in performing their anchoring function, the anchoring faces of the respective pairs when in anchoring position lying in substantially parallel relation with a common plane which passes between the pairs, the pivoted relation of the pairs being such that when in anchoring position the surface areas of the anchoring faces cooperate to substantially increase the total anchoring face area of the anchor, and the pivotal points of the pairs of leaves being adjacent one another.

9. In an anchor of the class described, a rod, a member movably mounted thereon and carrying an expansible anchoring means, a toggle mechanism for expanding said anchoring means including a sleeve mounted on the rod, a nut received in threaded engagement with the lower end of the rod for limiting movement of said sleeve in one direction, and whereby when the member is moved in a direction towards the sleeve, the toggle mechanism is operated to expand the anchoring means, oppositely disposed downward extensions on the lower end of the sleeve for preventing relative rotation of the nut with respect to the sleeve, and a wire element secured to said extensions below the nut and positioned in the path thereof, thereby to prevent relative downward movement of the rod in the sleeve, when the anchor is inserted into a hole in the ground, said wire element being adapted to yield to allow free translation of the rod through the sleeve, when a driving force is applied to the upper end of the rod.

THOMAS K. CUMMINS.
